UNITED STATES PATENT OFFICE

ALLAN CHENEY, OF MELROSE, MASSACHUSETTS

METAL FLASHING

Application filed December 2, 1930. Serial No. 499,498.

My invention relates to improvements in interlocking flashing, which is preferably constructed of sheet metal and made in a transverse ribbed form, the form being such that when embedded in mortar between two courses of masonry, the mortar serving as a bonding agency, there will be a mechanical bond between the contiguous courses of masonry.

10 The objects of my invention are to provide a form of flashing having ribs formed at an angle to the surface of the sheet of metal and extending transversely of its surface, for the purpose of holding the sheets 15 of metal straight across their transverse section, thereby to prevent their sagging in the center and form pockets to hold moisture.

Another object is to provide a ribbed reinforcement composed of a plurality of thicknesses of the metal, when the edges of the 20 flashing are bent laterally to form a flange extending along a side of the sheet.

A further object of my invention is to provide ribs extending above or below the 25 surface of the sheet at frequent intervals in order to prevent moisture from spreading lengthwise of the sheet. Other objects will appear in the description.

My invention comprises an improved form 30 of flashing as will be shown in the following specification and particularly pointed out in the claims forming a part thereof.

In the drawings:

Figure 1 is a perspective view showing 35 the preferred form of my improved flashing, one end of which is cut away, the other end showing the interlocking upturned edge.

Fig. 2 represents a section of two courses 40 of masonry with my improved flashing embedded in the bonding mortar, showing the meeting ends of two sheets of flashing with their ends interlocked.

Fig. 3 is a transverse sectional elevation 45 showing my improved flashing extending laterally in a wall of masonry, the flashing being embedded in the bonding mortar, its edges bent laterally against the face wall of the masonry to form a ribbed flange.

50 Fig. 4 is a sectional edge view of my im-

proved flashing showing the preferred form of rib.

Fig. 5 is a section of a modified form of flashing embodying my improvement.

Figs. 6, 7, 8, 9 and 10 show different forms 55 in which the ribs may be made without departing from the spirit of my invention.

As illustrated in the preferred form of my invention figures 1-11 represent the body of a sheet of flashing, 12, 12-12 etc., are a series of anchoring means, such as ribs inclined from a vertical line as better shown in Figs. 2 and 4 and generally of saw-toothed form. The anchors or ribs 12, etc., may be formed at an angle to the edge of the sheet so that the 60 spaces between them are wedge shape, tapering in opposite directions progressively (see Fig. 1) although the ribs may be formed parallel to each other as shown in Fig. 5 as desired.

The spaced ribs provide anchoring means affording a permanent bond between the metal flashing and the masonry structure and the walls 13-13-13 etc., may be inclined from the vertical to any desired degree or otherwise shaped to provide undercut portions for the reception of mortar to assist in the permanency of the bond. The 65 form which I prefer is best illustrated in Figs. 2-4 and 9. This preferred method of forming the ribs 12-12-12 etc., has many advantages, among others it serves to maintain the metal 14-14-14 etc., between the 70 ribs flat and straight transversely and free from hollows and pockets to catch and hold moisture; it also causes the metal in the spaces 14-14-14 etc., to incline lengthwise of the sheets so that troughs 15-15-15 etc., are formed at the junction of the vertically 75 inclined portion 13-13-13 etc., of the ribs and the horizontally inclined portion 14-14-14 etc., so that any moisture that may gather on the portions 14-14-14 etc., will readily flow to the troughs 15-15-15, etc., and readily drain to the outside of the wall.

The walls in which my improved flashing is used may consist of bricks, natural or artificial stone or the like. In Figs. 2 and 3 I have shown sections of walls composed of 80 bricks 16-16 etc., bonded together by layers 85 100

of mortar 17—17 etc., in which the flashing 14 is embedded. The edge of the flashing 14 is bent downward to form a flange 18 the ribs 12—12—12 etc., being flattened down to form reinforcing plait extending transversely of the flange 18.

Referring to Figs. 6 to 10 inclusive one or more of the ribs 19 in each figure may be partially or completely flattened down. When flattened down each rib is composed of overlapping portions of the flat portion, with the inclined portion of the rib interposed, thus making a reinforcing plait composed of a plurality of thicknesses of metal.

Successive sheets of flashing are interlocked as shown in Fig. 2, to form a strip of flashing from end to end of a masonry wall. The interlocking portions of the flashing are best illustrated in Figs. 2 and 9 wherein the end 20, is bent upwardly at substantially the same angle as the inclined portion 13, etc., of the ribs 12, etc., the opposite end 21, being bent downwardly at a corresponding angle. When two sheets are interlocked as shown in Fig. 2 the end 21, of one sheet hooks over and interlocks with a rib 12, the upturned end 20 of the second sheet rests against the under side of the first sheet. By this arrangement a trough 22, is formed that will hold any moisture that may pass under and around the hook portion 21. It is pointed out that the flat portion 23, is shorter than the portion 24, and the upturned edge 20 is positioned at right angle to the edge of the sheet 14. The down turned edge 21 is positioned at an angle to the edge of the sheet 14 corresponding to the angle of the rib 12 with which it interlockingly engages.

In view of the above it will be noted that I have provided a metal flashing of the through-wall type, that is, which extends transversely entirely through the wall, so as to drain moisture to the outside, with means for providing an adequate mechanical bond between the flashing and wall. In providing anchoring means by reversely bending the metal in Z-shaped or like form, relatively large inclined drainage areas are provided for the moisture of infiltration, leading to the drainage grooves 15. In providing symmetrical bends or anchoring means for the sheet, there is an economy in manufacture and a wide range of spacings between adjacent anchors is possible.

I have shown my improved flashing with the flat portion slanting upwardly from left to right, it may be formed however with the flat portion slanting upwardly from right to left or the portion 14; that is shown as flat may be curved lengthwise of the sheet, and likewise the reverse bands in the metal may obviously be S-shaped instead of Z-shaped transversely of the sheet, without departing from my invention.

My invention is not confined to the exact

form and size of ribs as shown, as both size and form of the ribs may be modified to meet special requirements, without departing from the spirit of my invention.

What I claim is:

1. Through-wall flashings for insertion between layers of masonry and adapted to extend through the masonry or like walls for intercepting and draining outwardly moisture that may infiltrate through said masonry, said flashing consisting of a sheet of metal bent to form a series of ribs extending transversely of the sheet formed of relatively short, upwardly inclined portions and adjacent relatively longer longitudinally inclined portions, the latter providing inclined drainage areas terminating in channels contiguous to said ribs to catch and convey away any moisture that may infiltrate to the surface of said sheet.

2. Through-wall flashings for insertion between the layers of masonry and the like walls, and adapted to extend entirely through said walls for intercepting and forming drainage channels to convey away moisture that may infiltrate through said masonry, consisting of a sheet of metal bent to form a series of transverse ribs, having upwardly extending inclined portions with substantially horizontally longer lateral portions between them, the upwardly inclined portions providing opposite reversely extending recesses serving to form an interlocking engagement with the masonry and to form channels to collect and convey away any moisture that might infiltrate through the masonry.

3. A masonry wall structure including superposed courses of masonry bound together by joints of mortar and a sheet metal flashing embedded in the mortar between certain of said courses, and extending substantially from side to side of said wall for intercepting moisture of infiltration in said wall, and a series of locking means substantially of saw-tooth shape bonding said flashing and masonry courses securely together and providing a series of oppositely inclined recesses for the reception of the mortar substantially symmetrical about the axis of the mortar joint, the correspondingly inclined recesses of adjacent locking means serving to provide a bond between the flashing sheet and mortar against shifting of the sheet longitudinally in one direction and the corresponding oppositely inclined recesses of adjacent locking means serving to prevent longitudinal shifting of the sheet in the opposite direction, both of said recesses serving to provide a bond against vertical movement of the sheet and superposed masonry.

4. A masonry wall structure provided with a through-wall flashing as set forth in claim 3 characterized by the provision of means for providing a permanent bond be-

tween said mortar and flashing preventing relative transverse shifting between the flashing and superposed courses of masonry.

5. Flashings for insertion between layers of masonry and the like, consisting of sheet metal of desired width to extend substantially from side to side of the masonry wall bent to form a series of relatively short ribs extending transversely of the sheet and at 10 an angle to its edges, and to each other, the metal adjacent to the top edge of one rib extending laterally and downwardly to the lower edge of the next adjacent rib to provide relatively long longitudinal portions between and connecting said ribs and drainage channels contiguous to said ribs to collect and convey away any moisture that may infiltrate to the surface of the sheet.

6. A sheet metal flashing adapted for insertion between layers of masonry comprising a plurality of sheet metal sheets of a desired width to extend substantially entirely through said masonry walls, and means for providing a mechanical bond between said 25 flashing sheet and wall, comprising a plurality of spaced anchoring means, each composed of relatively short ribs and longer intervening spaces to form oppositely extending reentrant recesses on opposite sides of said sheet, for the reception of mortar to 30 secure said flashing sheet against movement in opposite directions longitudinally of the sheet, areas of said sheets between said anchoring means being longitudinally inclined 35 from one towards the other to facilitate drainage of moisture from the interior of said wall.

7. Flashings for insertion between layers of masonry and the like, consisting of sheet metal of desired width to extend substantially from side to side of the masonry wall bent to form a series of relatively short ribs extending transversely of the sheet, certain of said ribs being arranged obliquely of the 45 sheet and angularly disposed with relation to others of said ribs, the metal adjacent the top edge of one rib extending laterally and downwardly to the lower edge of the next adjacent rib to provide relatively long longitudinal portions between and connecting said 50 ribs and drainage channels contiguous to said ribs to collect and convey away any moisture that may infiltrate to the surface of the sheet.

8. Flashings for insertion between layers of masonry and the like, consisting of sheet metal of desired width to extend substantially from side to side of the masonry wall bent to form a series of relatively short ribs extending transversely of the sheet, said ribs 55 being arranged in a plurality of groups, the ribs of one group being irregularly disposed with relation to the ribs of another group, the metal adjacent the top edge of one rib extending laterally and downwardly to the 60 lower edge of the next adjacent rib to pro-

vide relatively long longitudinal portions between and connecting said ribs and drainage channels contiguous to said ribs to collect and convey away any moisture that may infiltrate to the surface of the sheet.
